PIPE WRENCH

Eugene Harry Legg, Bergoo, W. Va., assignor of
one-half to Claude M. Blankenship, Adrian,
W. Va.

Application September 3, 1943, Serial No. 501,169

1. Claim. (Cl. 81—106)

The present invention relates to new and useful improvements in pipe wrenches of the type comprising a stationary inner jaw and a slidable outer jaw cooperable with said inner jaw.

The primary object of the invention is to provide, in a manner as hereinafter set forth, a pipe wrench of the aforementioned character comprising unique means whereby the slidable outer jaw may be rapidly and accurately adjusted as desired.

Another very important object of the invention is to provide a pipe wrench of the character described embodying a novel construction and arrangement for swinging the outer jaw to open position relative to the stationary inner jaw, whereby application of the tool to the work and removal therefrom will be expedited.

Other objects of the invention are to provide an adjustable pipe wrench which will be comparatively simple in construction, strong, durable, highly efficient and reliable in use, compact, light in weight, and which may be manufactured at low cost.

All of the foregoing, and still further objects and advantages of the invention will become apparent from a study of the following specification, taken in connection with the accompanying drawings wherein like characters of reference designate corresponding parts throughout the several views, and wherein:

Figure 1 is a view in side elevation of a pipe wrench constructed in accordance with the present invention.

Figure 2 is a view in front elevation of the tool with a portion of the handle broken away.

Figure 3 is a longitudinal sectional view, taken substantially on the line 3—3 of Figure 2.

Figures 4 and 5 are cross-sectional views, taken substantially on the lines 4—4 and 5—5, respectively, of Figure 1.

Figure 6 is a detail view in perspective of the pin which connects the shank of the slidable outer jaw to the frame.

Referring now to the drawings in detail, it will be seen that the embodiment of the invention which has been illustrated comprises a handle 1 of suitable metal. The handle 1 may be of any suitable dimensions. On one end of the handle 1 is a toothed stationary inner jaw 2. The portion of the handle 1 which is adjacent the jaw 2 is provided, on its front, with a series of transverse grooves 3.

Formed integrally with the stationary inner jaw 2 and projecting rearwardly therefrom is a guide 4. As illustrated to advantage in Figure 3

of the drawings, the bore or passage in the guide 4 is formed to provide opposed, substantially V-shaped fulcrums 5.

A frame 6 is mounted for sliding and swinging movement on the portion of the handle 1 which includes the grooves 3. Toward this end, the frame 6 includes an integral eye 7 through which the handle 1 passes. Formed in the eye 7 is an integral, substantially V-shaped tooth 8 which is engageable selectively in the grooves 3 for securing the frame 6 in adjusted position for swinging movement on the handle 1.

A shank 9 is slidable in the guide 4 and rockable on the fulcrums 5. On the forward end of the shank 9 is a toothed outer jaw 10 which is cooperable with the stationary inner jaw 2. Threadedly mounted in the inner end portion of the shank 9 is a transverse, removable pin 11. As best seen in Figure 6 of the drawings, the pin 11 comprises a threaded intermediate portion 12 and smooth end portions 13 having slots 14 therein for receiving a screw driver. The inner end portion of the shank 9 projects into the frame 6. The smooth end portions 13 of the pin 11 project from the shank 9 and are engaged in slots 15 in the side walls of the frame 6 for pivotally and slidably connecting said shank to said frame.

A spring pressed plunger 16 is slidably mounted in the inner portion of the frame 6 and engaged with the back of the handle 1 for engaging the tooth 8 in the desired groove 3 and for rocking said frame 6 forwardly or outwardly on said handle. A spring pressed plunger 17 is slidably mounted in the inner rear portion of the guide 4 and engaged with the shank 9 for swinging same on the fulcrums 5 in a manner to open the jaw 10 or, in other words, to swing said jaw 10 away from the jaw 2.

It is thought that the operation of the tool will be readily apparent from a consideration of the foregoing. Briefly to adjust the slidable outer jaw 10, the frame 6 is swung to a position substantially at right angles to the handle 1 and pressure is exerted on the rear end thereof for disengaging the tooth 8 from the opposed groove 3 against the action of the spring pressed plunger 16. When the tooth 8 is thus disengaged, the frame 6 may be moved longitudinally on the handle 1 for adjusting the jaw 10. When pressure is removed from the frame 6, the plunger 16 immediately engages the tooth 8 in one of the grooves 3 and swings said frame forwardly. Thus, the frame 6 is cocked on the handle 1 with the tooth 8 engaged in one of the grooves 3. The plunger 17 normally maintains the shank 9 and the jaw 10

in the position of Figures 1 and 3 of the drawings. In this position, it will be observed that the pin 11 is engaged in the forward end portions of the slots 15, or, stated otherwise, in the end portions of the slots 15 which are adjacent the handle 1. Thus, the jaw 10 is held in open position and the tool may be readily applied to the work. When the tool is applied and the turning operation is started, the jaw 10 swings toward the jaw 2 for firmly gripping the work. The greater the pull on the handle 1, the tighter will be the grip taken on the work by the tool. Reverse movement of the handle 1 permits the plunger 17 to open the jaw 10, thereby facilitating disengagement of the tool from the work.

It is believed that the many advantages of a pipe wrench constructed in accordance with the present invention will be readily understood, and although a preferred embodiment of the tool is as illustrated and described, it is to be understood that changes in the details of construction may be resorted to which will fall within the scope of the invention as claimed.

What is claimed is:

A pipe wrench comprising an elongated handle having a toothed inner jaw on the outer end thereof and provided in its front edge with a longitudinal series of transverse grooves, a guide rigid with and projecting rearwardly from said

jaw, said guide having a bore extending in the same direction as the handle and providing opposed front and rear fulcrums in the guide, a frame mounted for sliding and limited swinging movement on the handle, said frame having an eye at the front through which the handle loosely passes and being provided in the front of the eye with a tooth selectively engageable in the grooves of the handle and affording a transverse fulcrum adjustable longitudinally of the handle and about which the frame may swing outwardly or inwardly, a shank slideable in and constantly contacted by both of the opposed fulcrums of the guide for rocking forwardly or rearwardly in the latter, said shank having a forwardly projecting outer jaw on the outer end thereof, means connecting the inner end of the shank to the rear of the frame for limited sliding movement forwardly or rearwardly relative to the handle and permitting the swinging of the frame relative to the handle and the shank, spring means in the eye of the frame inwardly of the tooth and engaging the back of the handle to swing the frame outwardly, and spring means in the guide inwardly of its opposed fulcrums and engaging the back of the shank to rock the latter in a direction to swing the outer jaw outwardly and rearwardly from the inner jaw.
